(72) Inventors: **Adam Garland**, Wakefield, MA (US);
Nicholas Christo, Mansfield, MA (US)

FOREIGN PATENT DOCUMENTS

(73) Assignee: **SharkNinja Operating LLC**,
Needham, MA (US)

CA 1047470 A 1/1979
CA 1084374 A 8/1980

(Continued)

(**) Term: **15 Years**

(21) Appl. No.: **29/888,820**

(22) Filed: **Apr. 5, 2023**

CLAIM

(51) LOC (15) Cl. **06-06**

The ornamental design for a stand as shown and described.

(52) U.S. Cl.

USPC **D6/682.1**

DESCRIPTION

(58) **Field of Classification Search**

USPC D7/402, 403; D6/672-673, 675-675.2,
D6/678, 678.1, 682-682.1

CPC A47J 36/34; A47J 37/0736; F24B 1/191;
F24B 1/193

See application file for complete search history.

(56) **References Cited**

FIG. 1 is a front perspective view of the stand in a first

assembly configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a bottom perspective view thereof; and,

FIG. 9 is a front perspective view of a stand in a second

assembly configuration.

In some implementations, the stand, as shown in FIGS. 1-9, includes extendable bottom portions of the legs. In some implementations, as shown in FIGS. 7 and 8, a bottom side of the stand includes a plurality of protruding rims. In some implementations, the stand, as shown in FIGS. 1-9 includes a movable portion that can be fixed in a horizontal position. The broken lines shown in the figures show features of the stand that form no part of the claimed design.
